(57) **CLAIM**

The ornamental design for a mobile computer work station, as shown and described.

DESCRIPTION

FIG. 1 is a perspective view of a mobile computer work station, showing my new design; the broken lines are for environmental purposes only and form no part of the claimed design.

FIG. 2 is a perspective view of the mobile computer work station shown in an opened configuration.

FIG. 3 is a top view thereof in a closed configuration.

FIG. 4 is a bottom view thereof in a closed configuration.

FIG. 5 is a front view thereof in a closed configuration.

FIG. 6 is a rear view thereof in a closed configuration.

FIG. 7 is a side view thereof in a closed configuration; and, FIG. 8 is a side view thereof opposite the side shown in FIG. 7 shown in a closed configuration.
